UNITED STATES PATENT OFFICE

2,554,975

REMOVABLE EXPELLER FOR COLLAPSIBLE TUBES

Jack Bendick, Winnipeg, Manitoba, Canada

Application February 12, 1947, Serial No. 727,993

1 Claim. (Cl. 222—95)

1

This invention relates to an article to facilitate in expelling the contents of a collapsible tube.

Collapsible tubes are the most popular type of container used for such products as toothpastes, shaving creams, face creams and innumerable miscellaneous products of paste or liquid form and have several advantages as a container. One of these advantages is that the contents can be dispensed in small quantities directly to the article or surface to which the contents are to be applied, eliminating the necessity of using the fingers or a separate applicator as generally is the case when the contents are in a jar or other type of container.

There are several disadvantages however:

Unless care is taken in squeezing out the contents of the tube, unsightly corrugated deformations entrap portions of the contents, causing waste, and frequently, because of these corrugations the tube develops fractures permitting the contents to work through to the surface resulting in wastage and also making the tube rather messy for subsequent use.

Various suggestions have been made for removing the contents of collapsible tubes but they have not achieved much success as they have been generally cumbersome and are generally attached to a wall or other fixed surface, and are not convenient to use. Some are simpler in design but must be applied before the tube is sealed at the bottom end and are only adaptable to be sold on the tube. This type is discarded with the tube.

The object of this invention is to provide an expeller for collapsible tubes which can be easily applied to a tube after it has been filled and sealed, and when the contents have been expelled, removed to be used again on another full tube.

Another object is to provide an expeller for collapsible tubes, which is easy and inexpensive to manufacture and has no moving parts.

A third object of the invention is to provide an expeller for collapsible tubes which flattens the tube as it is progressively moved upwardly from the bottom end to the top, thus eliminating the unsightly corrugations and deformations which are generally the result when no expeller is used.

A fourth object of this invention is to provide an expeller for collapsible tubes which expels the contents thoroughly thus eliminating waste.

A fifth object of the invention is to provide an expeller for collapsible tubes which does not require the use of both hands when expelling the

contents, but can be expelled by applying pressure to the tube just above the expeller, as in ordinary practice, with the fingers of one hand, while the other hand is left free. After this had been done several times the expeller is moved up the tube by holding the bottom end between the fingers of one hand while the expeller is slid up with the fingers of the other hand, forcing all the contents ahead of the expeller for easy ejection. This method has the advantage in that holding the tube in the hand and trying to move the expeller up the tube with the fingers of the same hand, in expelling the contents, is not an easy matter. This is particularly difficult where the contents are of rather stiff consistency.

Another object of this invention is to provide an expeller for collapsible tubes that will not slip down the collapsed portion of the tube but remains in position at all times, not requiring initial positioning before it can be used.

Another object of the invention is to provide an expeller which when applied to the tube does not interfere in any manner whatsoever with the packaging of the tube if the user desires to keep the collapsible tube in the original package or container.

Figure 1 is a front elevation of the expeller applied to a collapsible tube.

Figure 2 shows the metal blank from which the expeller is formed.

Figure 3 shows the metal blank after initial forming but before it is folded inwardly upon itself to form the expeller illustrated in the subsequent figures.

Figure 4 is an end elevational view of expeller at the open end.

Figure 5 is an end elevational view of expeller at closed end.

Figure 6 is a front elevational view of fastening member.

Figure 7 is a top elevational view of expeller with fastening member on.

Figure 8 is a top elevational view of expeller broken on the line 8—8, Figure 7, showing open end with fastening member removed.

Figure 9 is method of manufacture of fastening member from the tubular piece having a slot of suitable width.

Figure 10 is a vertical sectional view on the line 10—10 of Figure 7.

Like numerals of reference designate corresponding parts throughout the specification and drawings.

The numeral 10 indicates a collapsible tube

from which part of the contents have been expelled and shows the expeller applied thereto. The expeller is formed from a single piece of sheet aluminum or other suitable relatively thin sheet material of the required dimensions, this blank being shown in Figure 2. The blank is pressed into the desired shape so that when the metal blank is bent upon itself midway between its ends it will conform substantially to the shape of the collapsible tube in the area from which part of the contents have been expelled, as hereinafter specifically described.

As shown in Figures 4 and 5 expeller sides 11 converge inwardly and near the bottom edge thereof, diverge outwardly to form a pair of parallel lips 12 with a narrow slot 13 formed between the lips 12. The particular shape adds rigidity to the sides 11 which is necessary to prevent the contents of the tube from by-passing the lips to the collapsed portion of the tube when pressure is applied. Each end of the blank shown in Figure 2 is formed with diverging wings 14, 15 respectively, which are fastened together by means of a slotted clip 16. These diverging wings permit easier application of the expeller to the tube and prevent the slotted clip from being pulled sideways off the expeller, which will be in a direction at right angles to the normal method of applying the slotted clip to the body of the expeller or in removing it. Near the base of the wing 14 is formed a stud 17 stamped out of the material and which fits into an indentation 18 formed in the base of the wing 15. The indentation 18 does not protrude to the opposite side of the wing but is made in the metal itself and does not interfere with slipping the slotted clip 16 over the wings 14, 15.

The blank is also shaped so that when it is folded inwardly upon itself the ends 19, 20 will have the top edge flared outwardly as indicated at 21, 22 to prevent the expeller from cutting into the tube as it is moved upwards. The ends 19, 20 are also inclined inwardly as illustrated which prevents the expeller from slipping down when pressure is applied to the tube in expelling the contents or in subsequent handling. The slot 13 is wide enough at both ends to permit the collapsed portion of the tube to pass therethrough the width being approximately .018 inch. The width of the slot midway between the ends 19,

20 need not be as wide since the slight springing tension of the lips 12 permit them to give sufficiently to provide a proper pressure on the tube to force all contents before the expeller.

5 The slotted clip 16 is tubular in construction with a slot 23 just wide enough to slip over the two thicknesses of the metal of the expeller and fits over the diverging wings 14, 15. The lower end of the slot 23 is slightly chamfered to permit 10 easy insertion onto the expeller and the upper end is compressed or crimped to prevent the clip 16 from being slipped too far over the wings 14, 15.

In manufacturing the clip 16, a tubular member 24 with a slot of suitable width is cut into proper lengths as shown in Figure 9 with a suitable instrument which will cut one end without deforming or compressing the walls of the tubular member and will apply a compressing action to 20 the other end during the cutting operation to narrow the slot.

What I claim as new and desire to protect by Letters Patent of the United States is:

25 A removable and reusable expeller for a collapsible tube comprising a member having side and end walls, said side walls being arcuately curved to conform to the curvature of the outside surface of the tube and terminating at their lower edge in a pair of lips forming a longitudinal slot therebetween, the end walls being arcuately curved to conform to the shape of the sides of the tube, one of said end walls being divided vertically to form a pair of free ends, a laterally projecting portion on each free end, 30 each of said projecting portions having a groove 35 on its outer surface, and a U-shaped member adapted to slide at a right angle over said laterally projecting portions in said grooves and secure them together.
